(57) **CLAIM**

The ornamental design for a relay for lighting control, as shown and described.

DESCRIPTION

FIG. 1 is a top, rear, and left side perspective view of the design according to the invention.

FIG. 2 is a top, front, and right side perspective view of the design according to the invention.

FIG. 3 is a top view of the design according to the invention.

FIG. 4 is a bottom view of the design according to the invention.

FIG. 5 is a front view of the design according to the invention.

FIG. 6 is a rear view of the design according to the invention.

FIG. 7 is a right side view of the design according to the invention.

FIG. 8 is a left side view of the design according to the invention; and,

FIG. 9 is a sectional view of the design according to the invention taken along line “9—9” in FIG. 3.
